UNITED STATES PATENT OFFICE.

NATHAN FUCHS, OF CHICAGO, ILLINOIS, ASSIGNOR OF ONE-HALF TO HARRY D. KIRK,
OF CHICAGO, ILLINOIS.

STETHOSCOPE.

965,174.

Specification of Letters Patent. Patented July 26, 1910.

Application filed October 13, 1909. Serial No. 522,405.

To all whom it may concern:

Be it known that I, NATHAN FUCHS, a citizen of the United States, residing at Chicago, county of Cook, and State of Illinois, have invented certain new and useful Improvements in Stethoscopes, of which the following is a specification.

My invention relates to improvements in stethoscopes and has for its object the production of a stethoscope of improved construction and operation.

The invention consists in the combination and arrangement of parts hereinafter described and claimed.

15 My invention will be best understood by reference to the accompanying drawings forming a part of this specification, and in which,

20 Figure 1 is a perspective view of a stethoscope embodying my invention but showing the ear tubes as partially broken away, Fig. 2, an elevation of the stethoscope partially in section, Fig. 3, an elevation at right angles to Fig. 2 with the ear tubes broken away, and Fig. 4, a longitudinal section of Fig. 2.

25 In the preferred form of construction as illustrated in the drawings, a central valve casing 1 is provided with oppositely disposed diaphragm chambers 2 and 3 screw-threaded thereto. Each of said chambers is closed on its outer side by flexible diaphragms 4 and 5 respectively which are secured in position by means of threaded caps 6 and 7 respectively, as shown in Fig. 4. Passages 8 and 9 place each of said diaphragms in open communication with the interior of valve casing 1. At one side valve casing 1 is provided with the supplemental chamber 10 also in communication with the interior of said casing. Nipples 11 are threaded into the walls of chambers 10 and serve as a means for securing the ends of ear tubes 12 which carry ear pieces 13 at their outer ends. Within casing 1 is mounted a rotary valve plug 14 which is provided with passages or ports 15 by means of which either of the chambers 2 and 3 may be thrown into communication with chamber 10. Plug 14 is preferably secured in said housing by means of a thumb screw 16 threaded into the end of said plug which is depending in form as shown. At its other end plug 14 is provided with a knurled head 17 which is preferably provided with

suitable letters or other markings to indicate which of the stethoscopic chambers is in communication with supplemental chamber 10.

In use it will be seen that either of the stethoscopic chambers 2 or 3 may be thrown into communication with chamber 10 and thus with the ears of the operator through ear tubes 12. Thus the operator is enabled to readily examine different portions of the anatomy with either chamber as desired.

60 While I have illustrated and described the preferred construction for carrying my invention into effect this is capable of variation and modification without departing from the spirit of my invention. I therefore do not wish to be limited to the exact 65 details of construction set forth but desire to avail myself of such variations and modifications as come within the scope of the appended claims.

70 Having described my invention what I claim as new and desire to secure by Letters Patent is:

75 1. In a stethoscope, the combination of larger and smaller diaphragm chambers, a 80 valve chamber in permanent communication with each of said diaphragm chambers; a supplemental chamber in open communication with the valve chamber; ear tubes communicating with said supplemental chamber; and a valve in said valve chamber 85 adapted to throw one of said diaphragm chambers into communication with said supplemental chamber and cut off communication with the other diaphragm chamber, 90 substantially as described.

2. In a stethoscope, the combination of a valve casing; oppositely disposed larger and smaller diaphragm chambers communicating with said valve casing; a supplemental chamber on said casing and communicating with said valve casing; ear tubes permanently communicating with said supplemental chamber; and a rotary valve in 95 said casing adapted to throw one of said 100 diaphragm chambers into communication with said supplemental chamber and cut off communication with the other diaphragm chamber, substantially as described.

3. In a stethoscope, the combination of a 105 valve casing containing a valve chamber; oppositely disposed larger and smaller diaphragm chambers communicating with said valve chamber by oppositely disposed channels in axial alignment with each other; a 110

supplemental chamber on said casing separate from said valve chamber but communicating therewith through a channel at right angles to said first mentioned channels; ear tubes communicating with said supplemental chamber; and a rotary valve in said valve chamber having passages at right angles to each other and adapted to throw either of said diaphragm chambers into communication with said supplemental chamber and to cut off communication between the other diaphragm chamber and said supplemental chamber, substantially as described.

4. In a stethoscope, the combination of a valve casing; oppositely disposed larger and smaller diaphragm chambers communicating with said valve casing by oppositely disposed channels in axial alinement with each other; a supplemental chamber on said cas-

ing and communicating therewith through a channel at right angles to said first mentioned channels; ear tubes communicating with said supplemental chamber; and a rotary valve in said casing having passages at right angles to each other and adapted to throw either of said diaphragm chambers into communication with said supplemental chamber and to cut off communication between the other diaphragm chamber and said supplemental chamber, substantially as described.

In testimony whereof I have signed my name to this specification in the presence of two subscribing witnesses.

NATHAN FUCHS.
